(57) **CLAIM**

The ornamental design for a protective CD cover, as shown and described.

DESCRIPTION

FIG. 1 is a front view of the protective CD cover showing my new design;

FIG. 2 is a left end view thereof;

FIG. 3 is a right end view thereof;

FIG. 4 is a rear view thereof;

FIG. 5 is a bottom view thereof; and,

FIG. 6 is a top view thereof.

The broken line showing of the CD is included for the purpose of illustrating environment and forms no part of the claimed design.
